BASCUM O. AUSTIN, OF WILKINSBURG, PENNSYLVANIA, ASSIGNOR TO WESTINGHOUSE ELECTRIC & MANUFACTURING COMPANY, A CORPORATION OF PENNSYLVANIA

CONTROL APPARATUS

Application filed March 26, 1925. Serial No. 18,635.

My invention relates to improvements in control apparatus and more particularly to arc-rupturing devices of the type generally used for breaking electric circuits of high amperage.

The object of the invention, generally stated, is the provision of an arc-rupturing device that shall be simple and efficient in operation and readily and economically manufactured.

A more specific object of the invention is to provide for the continual strengthening of an arc-rupturing field during the process of disruption to limit the travel of an arc.

15 A further object of this invention is to provide for the detachable mounting of the different members of the arc-rupturing device to facilitate its assemblage.

Other objects of the invention will in part 20 be obvious and in part appear hereinafter.

The invention, accordingly, is disclosed in the embodiment thereof shown in the accompanying drawings and comprises the features of construction, combination of elements and 25 arrangement of parts which will be exemplified in the construction hereinafter set forth and the scope of the application of which will be indicated in the claims.

For a more complete understanding of the 30 nature and objects of the invention, reference should be had to the following detailed description taken in connection with the accompanying drawings, in which

Figure 1 is a view in side elevation of one 35 embodiment of the arc-rupturing device constructed in accordance with this invention;

Fig. 2 is a view in side elevation of the 40 upper portion of the arc-rupturing device, parts being cut away to show its construction;

Fig. 3 is a sectional view along the line III—III of Fig. 1.

Referring now to the drawings, the illustrated 45 arc-rupturing device comprises a pair of spaced rods 10 and 11 which serve as a frame for carrying various parts of the structure. Many different attachments may be provided for mounting the frame on different supports and in this embodiment of the in-

vention, hangers 12 are provided and attached to the upper ends of the rods.

The hangers comprise rectangular bands 13 provided with threaded openings and pinned to the upper ends of the rods, as 55 shown at 14. Therefore, the frame may be removably suspended from any support, such as an angle bar 15, by means of screws 16 adapted to engage in the threaded openings provided in the rectangular bands. 60

In order to insulate the various contact members and arc horns, to be described hereinafter, from the bars to prevent grounding, insulating casings 17 are mounted on the latter. These insulating members may be constructed from any suitable insulating material, such as micarta, which is adapted to stand strains such as may be applied by clamping the members of the arc-rupturing 65 device thereon.

The upper arc horn, shown generally at 18, comprises a single casting, the forward portion of which is substantially U-shape while the rear portion is shaped to seat on the insulating casings 17 carried by the rods 70 and 11. In order to clamp the casting in any desired position on the rods 10 and 11, a plate 19, shaped to seat on the insulating casings 17, is provided and connected to the casting by means of a screw bolt 20. 75

As shown, a stud 21 is mounted in an extension of the arc horn casting and serves to carry a terminal 22 provided for electrically connecting any conductor to the arc horn. Depending from the stud 21 is a block 22', of 80 insulating material, which serves as a panel for carrying a second terminal member 23, to which a flexible conductor 24 is attached.

As will be observed, the U-shaped arc horn, shown generally at 18, includes spaced arms 85 25 and 26. The arm 26, being integral with the body of the casting, serves as a feed-conductor while the outer arm 25 is disposed to receive an arc from a contact member 27 attached to the casting at the juncture of the 90 arms 25 and 26.

In this particular embodiment of the invention, a projection is provided on the arm 25 and is located near the outer end of the latter. As will be readily understood, when

the end of an arc reaches this projection it will be carried outward with the body of the arc which is continually forced outward by the arc-rupturing field. However, while a 5 projection is provided in this particular construction, it is not essential in the building of an efficient arc-rupturing device.

In order to provide an arc-rupturing field, a U-shaped core 28 is disposed in the arc 10 horn 18 so that its parallel-extending arms 51 and 52 project forward. The extent of the arc-rupturing field may be extended by attaching to the arms of the core, pole pieces 29 and 30. In the construction illustrated, 15 the pole pieces 29 and 30 are supported on the core 28 by means of bolts 53 which extend through both members.

As will be observed, the core 28 is insulated from the arc horn 18 by an insulator 31. 20 The insulator may be made from some flexible insulating material and mounted on the core either before or after it is shaped.

The operation of the arc-rupturing device may be effected by an air engine 32 suspended 25 from the rods 10 and 11 in any suitable manner, such as by the use of bolts 33. Air engines of this type are well known in the art and further description is considered unnecessary.

30 As will be noted, a casting 33' is carried by the plunger 34 of the air engine 32. Formed integral with the forward portion of the casting 33' is an arc horn of substantially U-shape, shown generally at 35.

35 As shown, the arc horn 35 includes spaced arms 36 and 37. The forward arm 36 is somewhat longer than the rear arm 37. As set forth, the arc horn is formed integral with the casting 33, but it will be readily understood 40 that the arc horn may be formed as a separate unit and removably attached to the casting. In order to concentrate the lines of magnetic force induced by current flowing in the arc horn 35, a core 38 is disposed 45 between the arms of the arc horn and fixed to the forward arm 36 in any suitable manner, such as by the use of screws.

In order to concentrate the lines of magnetic force emanating from the core 38, pole 50 pieces 40 are supported from the pole pieces 29 and 30 and disposed to lie in the same planes. In this particular embodiment of the invention, the pole pieces 40 are attached to connecting members or plates 50 and the 55 latter to pole pieces 29 and 30 by bolts 54. The pole pieces 40 are mounted to lie close to the ends of the core 38 so that lines of magnetic force induced in the core are collected by the pole pieces 40 and concentrated to form 60 an arc-rupturing field about the arc horn 35.

Pole pieces 40 are suspended from the pole 65 pieces 29 and 30. These pole pieces 40 extend in the planes of the corresponding pole pieces 29 and 30. Thus, the lines of magnetic force induced in the core 38 are distributed,

forming an arc-rupturing field in which the lower arc horn 35 is disposed.

The rear portion of the casting 33' is provided with spaced upwardly-extending arms 41. As shown, a block 42 is trunnioned in 70 the arms 41 to permit an oscillatory movement of the former. A contact member 43 is fixed to the block 42 and is located in alignment with the contact member 27.

In order to provide for a wiping engagement between the contact members 27 and 43, a spring 44 is mounted between a downwardly-extending arm provided on the block 42 and a set-screw 50 mounted in the rear portion of the casting 33'. This spring serves to retain the contact member 43 inclined at an angle to the face of the contact member 27 when the contact members are separated.

The lower end of the flexible conductor 24 is connected to the block 42 to establish electrical connection between the contact member 43 and the terminal 23. This permits an oscillatory movement of the block 42 as the contact member 43 is projected upward on the operation of the air engine.

In order to protect the pole pieces 29, 30 and 40, an arc chute 45 of rectangular cross section is provided. As shown in Fig. 1, the arc chute is set between the oppositely-disposed pole pieces and rests on an arm 46 formed integral with the casing of the air engine.

The arc chute may be retained in position in any suitable manner, such, for example, as by providing a depending latch 47, which may be engaged by a bolt 48 pivotally mounted on the arm 46. A nut 49 is provided on the bolt 48 to lock the latch 47.

Assume that it is desired to close a circuit through the arc-rupturing device. Then the 105 air engine is operated to project the piston 34 upward. As the piston moves upward, the forward end of the contact member 43 engages the contact member 27 and the block 42 is oscillated, causing the contact member 43 to slide on the contact member 27 and to finally engage the latter throughout its length. Current now flows from the terminal 22 through the arm 26 of the arc horn 110 18, contact member 27, contact member 43, the block 42 and the flexible conductor 24 to the terminal 23.

In order to break the circuit, the air engine is again operated to separate the contact members 43 and 27. When the contact members are separated, an arc is drawn between them. Since the spring 44 was compressed during the closing of the contact members, it functions to oscillate the block 42 as the contact members are separated. The inclining of the contact member 43 to the horizontal tends to force the arc to the tips of the contact members.

The current flowing in the rear arm of the arc horn 18 induces a magnetic flux in the 130

core 28, which is distributed through the pole pieces 29 and 30, building up a magnetic field which tends to force the arc outward. Consequently, the arc is then delivered to the arc horns 18 and 35. When the arc is located between the arc horns, current flows from the contact terminal 22 through the arm 26 of the arc horn 18, the arm 37 of the arc horn 35 and back through the casting 33' and flexible conductor 24 to the terminal 23. Thus, a magnetic flux is induced in the core 38, building up an arc-rupturing field about the arc horn 35.

It will be understood that as the ends of the arc travel outward along the arms 25 and 36 of the arc horns 18 and 35, respectively, the length of the energized conductors which induce magnetic flux in the cores 28 and 38 is continually increased. Consequently, the flux induced in the cores is continually increased, thereby continuously strengthening the arc-rupturing field, or in other words, the total number of lines of flux in the arc-rupturing field continuously increases after the arc has been drawn and during the rupturing process.

Finally, the strength of the magnetic field is so increased that it effects a disruption of the arc.

Since various changes may be made in the above-described construction and arrangement of parts, and different embodiments of the invention may be made without departing from the scope thereof, it is intended that all matter contained in the above description or shown in the accompanying drawings shall be interpreted as illustrative and not in a limiting sense.

I claim as my invention:

1. In an arc-rupturing device, in combination, a plurality of relatively movable arc horns, cores adapted to concentrate the lines of magnetic force induced by current flowing through the arc horns to provide an arc-rupturing field, said arc horns being looped about the cores to strengthen the arc-rupturing field as arcs travel along them.

2. In an arc-rupturing device, in combination, a plurality of relatively movable arc horns, contact members carried by the arc horns, said arc horns being substantially U-shaped, one arm of each serving as a feed conductor for the corresponding contact member, cores disposed between the arms of said arc horns for concentrating the lines of magnetic force induced by the current flowing through the arc horns to provide an arc-rupturing field.

3. In an arc-rupturing device, in combination, a frame, an arc horn carried by the frame, a core for concentrating lines of magnetic force induced by current flowing in the arc horn, said arc horn being shaped to receive the core and to form a loop about it,

thereby to induce a gradually increasing flux as an arc travels along the arc horn.

4. In an arc-rupturing device, in combination, a frame, an arc horn carried by the frame, said arc horn being substantially of U-shape, one arm being disposed to serve as a feed conductor, a core mounted between the arms of the arc horn, said core being adapted to concentrate lines of magnetic force induced by current flowing in the arc horn, and pole pieces carried by the core to distribute the lines of magnetic force to provide an arc-rupturing field.

5. In an arc-rupturing device, in combination, a frame, an arc horn carried by the frame, said arc horn being substantially of U-shape, one arm being disposed to serve as a feed conductor, a core mounted between the arms of the arc horn, said core being adapted to concentrate lines of magnetic force induced by current flowing in the arc horn, pole pieces carried by the core to distribute the lines of magnetic force to provide an arc-rupturing field, and a fixed contact member mounted on the arc horn at the point of juncture of the arms.

6. In an arc-rupturing device, in combination, a frame, an arc horn carried by the frame, said arc horn being substantially of U-shape, one arm being disposed to serve as a feed conductor, a core mounted between the arms of the arc horn, said core being adapted to concentrate lines of magnetic force induced by current flowing in the arc horn, pole pieces carried by the core to distribute the lines of magnetic force to provide an arc-rupturing field, and a fixed contact member mounted on the arc horn at the point of juncture of the arms, a movable contact member disposed in alignment with the fixed contact member and an arc horn disposed to move with said movable contact member.

7. In an arc-rupturing device, in combination, a frame, an arc horn carried by the frame, said arc horn being substantially of U-shape, one arm being disposed to serve as a feed conductor, a core mounted between the arms of the arc horn, said core being adapted to concentrate lines of magnetic force induced by current flowing in the arc horn, pole pieces carried by the core to distribute the lines of magnetic force to provide an arc-rupturing field, and a fixed contact member mounted on the arc horn at the point of juncture of the arms, a movable contact member disposed in alignment with the fixed contact member, a substantially U-shaped arc horn mounted to move with the movable contact member.

8. In an arc-rupturing device, in combination, a frame, an arc horn carried by the frame, said arc horn being substantially of U-shape, one arm being disposed to serve as a feed conductor, a core mounted between the arms of the arc horn, said core being adapted

- to concentrate lines of magnetic force induced by current flowing in the arc horn, pole pieces carried by the core to distribute the lines of magnetic force to provide an arc-rupturing field, and a fixed contact member mounted on the arc horn at the point of juncture of the arms, a movable contact member disposed in alinement with the fixed contact member, a substantially U-shaped arc horn mounted to move with the movable contact member and a core fixed between the arms of the movable arc horn.
9. In an arc-rupturing device, in combination, a frame, an arc horn carried by the frame, said arc horn being substantially of U-shape, one arm being disposed to serve as a feed conductor, a core mounted between the arms of the arc horn, said core being adapted to concentrate lines of magnetic force induced by current flowing in the arc horn, pole pieces carried by the core to distribute the lines of magnetic force to provide an arc-rupturing field, and a fixed contact member mounted on the arc horn at the point of juncture of the arms, a movable contact member disposed in alinement with the fixed contact member, a substantially U-shaped arc horn mounted to move with the movable contact member and a core fixed between the arms of the movable arc horn, said core being disposed to move between the pole pieces, thereby to strengthen the magnetic field during the process of disruption.
10. In an arc-rupturing device, in combination, a frame, an arc horn carried by the frame, said arc horn being substantially of U-shape, one arm being disposed to serve as a feed conductor, a core mounted between the arms of the arc horn, said core being adapted to concentrate lines of magnetic force induced by current flowing in the arc horn, pole pieces carried by the core to distribute the lines of magnetic force to provide an arc-rupturing field, and a fixed contact member mounted on the arc horn at the point of juncture of the arms, a movable contact member disposed in alinement with the fixed contact member, a substantially U-shaped arc horn mounted to move with the movable contact member and a core fixed between the arms of the movable arc horn, said core being disposed to move between the pole pieces, thereby to strengthen the magnetic field during the process of disruption, and an arc chute adapted to be removably mounted on the frame to extend between the pole pieces and the arc horns.
11. In an arc-rupturing device, in combination, an arc horn, a core disposed to concentrate the lines of magnetic force induced by current flowing in the arc horn to provide an arc-rupturing field, said arc horn being looped about the core to strengthen the arc-rupturing field as an arc travels outwardly along the arc horn.
12. An arc-rupturing device comprising a pair of separable contact members, horns disposed adjacent to the respective contact members and electrically connected thereto, respectively, and arc-breaking means for blowing the arc out along said horns after the separation of said contact members characterized by the fact that said arc-breaking means comprises a U-shaped core of magnetizable material, the bight of said U-shaped core being disposed in juxtaposition to one of said horns so that the latter extends partially around the periphery of said bight, the legs of the U terminating in pole pieces straddling said arc to blow the same along the horns, means being provided for giving the arc its initial displacement from said contact members to said horns and partially along the latter, whereby the current thereafter flowing in said one of the horns from the associated contact member to the terminus of the arc, produces a magnetizing action which increases as the arc moves along said horn.
13. An arc-rupturing device comprising a pair of separable contact members, horns disposed adjacent to the respective contact members and electrically connected thereto, respectively, and arc-breaking means for blowing the arc out along said horns after the separation of said contact members characterized by the fact that said arc-breaking means comprises a U-shaped core of magnetizable material, the bight of said U-shaped core being disposed in juxtaposition to one of said horns so that the latter extends partially around the periphery of said bight, the legs of the U terminating in pole pieces straddling said arc to blow the same along the horns, means being provided for giving the arc its initial displacement from said contact members to said horns and partially along the latter, whereby the current thereafter flowing in said one of the horns from the associated contact member to the terminus of the arc, produces a magnetizing action which increases as the arc moves along said horn, said initial displacement means comprising a conducting member or lead connected to the contact member adjacent to said bight and extending around another portion of the periphery thereof.
- In testimony whereof, I have hereunto subscribed my name this 9th day of March, 1925.
- BASCUM O. AUSTIN.
